UNITED STATES PATENT OFFICE.

ALBERT ETIENNE, OF ST.-BENOIT-SUR-LOIRE, FRANCE, ASSIGNOR TO RAOUL LORY, OF PARIS, FRANCE.

APPARATUS FOR MAKING WIGS AND FALSE FRINGES.

1,017,253.

Specification of Letters Patent.

Patented Feb. 13, 1912.

Application filed February 28, 1910. Serial No. 546,527.

To all whom it may concern:

Be it known that I, ALBERT ETIENNE, a citizen of the French Republic, and resident of St.-Benoit-sur-Loire, France, have invented 5 certain new and useful Improvements in Apparatus for Making Wigs and False Fringes, of which the following is a specification.

This invention relates to an improved apparatus for making wigs and fringes of hair of the type in which two branches of a wire tender between movable hooks and a fixed hook are wound one around the other to fix the bundles of hair between them.

15 In the accompanying drawings: Figure 1 is a side elevation of my improved apparatus. Fig. 2 shows the pincers open. Fig. 3 represents the pincers in closed position. Fig. 4 is a side view of the pincers. Fig. 5 20 shows in side elevation the cam-lever pressed down. Fig. 6 shows said cam lever in lifted position.

My improved apparatus consists of a supporting frame *b* in which a shaft *a* is rev- 25 olubly mounted. A toothed wheel *c* is keyed upon shaft *a* and engages (Fig. 1) with two pinions *e*, *e'* mounted upon a vertical support *d* fixed upon the axle or shaft *a*. This shaft is driven by means of the 30 hand wheel *f*. Two threaded tubes *g*, *g'* are fixed each upon one of the pinions *e*, *e'*. Upon said threaded tubes the nuts *i* are mounted which are composed each of two parts hingedly connected by means of a 35 hinge *k* and closed by a loop *l*. The upper part of the nut carries an eye *j* to which an end of the wire *t* is attached. The other part of the apparatus is composed of an up- 40 right support with a bearing *p* in which a horizontal sleeve *o* is mounted. In this sleeve *o* a shaft *m* is located which has an open hook *n* at its front end. The sleeve *o* and shaft *m* are secured against rotation. In the rear end of said shaft *m* a cotter *q* 45 is inserted destined to serve as abutment for one end of a spiral spring *r* whose other end abuts against the support *p*. A cam lever *s* is arranged at the end of said shaft *m* so that its cam can act upon said shaft. A 50 wire *t*, *t* is fitted at the middle to the hook *n* and with their ends each to one of the eye *j*.

This apparatus operates as follows:—

After the nuts *i* have been mounted upon the ends of the corresponding screw spindles 55 *g* they are locked by means of the hoops *l*.

One end of the wire *t* is attached to the eye *j* of the upper nut and the other end to the eye of the lower nut. The middle of the wire is placed on the hook *n* after the shaft *m* has been pushed forward owing to the 60 cam lever *s* being lifted. When the cam lever *s* is released the spring *r* pulls the shaft *m* back and the wire *t* is uniformly tensioned and holds the nuts *i*. If the hand wheel *f* is being turned, the screw spindles *g* are 65 turned in the vertical plane through the intermediary of the vertical support *d*; the bevel wheel *e* rolls simultaneously upon the fixed cog wheel *e* so that the screw spindles *g* revolve in opposite directions around their 70 own axes. As the nuts *i* cannot participate in the revolution of their screw spindles they move toward the shaft *a*; the two parts of the wire *t* being wound at the same time the one around the other. The pitch of the 75 threads of the screw spindles *g* and the bevel wheels are calculated so that the nuts approach one another uniformly, the angle formed by the two parts of the wire *t* remaining always the same. The parts of 80 wire *t* therefore will wind the one around the other for a determined length at each revolution of the hand wheel *f*. If a bushel of hair brushed on comb *v*, is placed between the two parts of a wire *t*, the bushel of hair 85 will be clamped in at the next revolution of the hand wheel *f*. The interval between two consecutive bushels of hair can be regulated by the revolutions of the hand wheel.

A comb *v* is arranged between the two 90 parts of the apparatus by means of which the hair is combed.

This improved apparatus is extremely simple and the work is done absolutely mechanically and with great exactness and accuracy.

I claim:

In an improved apparatus for making wigs and false fringes the combination of two fixed uprights having bearings at their 100 upper ends, with a shaft revolvably mounted in one of said bearings, a hand wheel for revolving said shaft, a bevel wheel fixed to said shaft, a support keyed upon said shaft, bevel wheels engaging with the fixed 105 bevel-wheel, mounted upon the ends of said support, screw spindles fixed upon said bevel-wheels, a nut upon each of said screw spindles carrying an eye each nut being composed of two parts, and a tube fixed in the 110

bearing of the other upright, an axle mov-
ably mounted in said tube, a hook fixed in
the front end of said axle, a cotter in the
rear end of said axle and a spiral spring in-
serted between said cotter and said bearing,
a cam lever behind the rear end of said axle
for pushing the same forward in compress-
ing said spiral spring, and a wire fixed with
one end to the eye of the upper nut guided
10 at the middle by said hook of the movable

axle and fixed with its other end to the eye
of the lower nut; substantially as described
and illustrated and for the purpose set forth.

In witness whereof I have hereunto set
my hand in the presence of two witnesses. 15

ALBERT ETIENNE.
